SELF-WRINGING MOP

Virgil K. Cooper, North Hollywood, Calif.

Application March 29, 1939, Serial No. 264,765

9 Claims. (Cl. 15—119)

My invention relates generally to mops, and more particularly to the type known as self-wringing mops.

The problem of wringing a mop to remove surplus water, without requiring the operator to get his hands dirty or wet, has engaged the attention of inventors for a number of years. Some have solved the problem by placing a squeezing apparatus on the side of the pail, but this creates a cumbersome, top-heavy arrangement which may be easily up-set. Others have attempted to solve the problem by providing wringing apparatus on the mop itself, but this has usually resulted in a mechanically complicated mop, or one requiring a special form of mop cloth.

It is a major object of my invention to provide a self-wringing mop which overcomes these disadvantages while being simple to use and positive in operation.

It is another object of my invention to provide such a mop which makes use of a simple mop cloth of any reasonable length.

It is also an object of my invention to provide a mop of this type which may be made almost entirely of metal stampings, thus appreciably reducing the cost of the mop.

These and other objects of my invention will become apparent from the following description of a preferred and optional form thereof, and from the drawings illustrating those forms, in which:

Fig. 1 is a utility view of my preferred form of mop,

Fig. 2 is a side elevation view, partly in section, taken at 2—2 in Fig. 1,

Fig. 3 is a plan view, partly in section, taken at 3—3 in Fig. 2,

Fig. 4 is a cross-sectional view taken at 4—4 in Fig. 3,

Fig. 5 is a perspective view of my preferred form of mop showing the box-like member and its associated clevis, with the square sleeve omitted,

Fig. 6 is a side view of a different type of yoke transfer means which may be used in place of that shown in the assembled mop,

Fig. 7 is a utility view of an optional form of my invention,

Fig. 8 is a cross-sectional view of my optional form taken at 8—8 in Fig. 9,

Fig. 9 is a plan view of my optional form,

Fig. 10 is a cross-sectional view taken at 10—10 in Fig. 9,

Fig. 11 is a perspective view of an optional form of handle, and

Fig. 12 is a view, partly in section, showing how a wooden extension may be attached to the handle shown in Figs. 7—9.

Referring now to the drawings, and particularly to Figs. 1—3 thereof, the numeral 10 indicates a handle, usually made of wood, upon which slides a circular sleeve 11 which is moved to effect the wringing of the mop. At the lower end of the handle 10 is a pair of rollers 12 and 13 between which passes a mop cloth 14 carried by a pair of rods 15 and 15a attached to the sleeve 11, the motion of the sleeve along the handle causing the cloth to be pulled between the rollers thus removing the surplus water from it. It is to be understood that the term "mop cloth" includes string-type mops and all materials, natural and artificial, used in place of cloth.

The roller 12 is carried by a clevis 16 which is attached at its center to a box-like member 17 attached to the forward end of the handle 10. Adjacent each side of the point of attachment to the box-like member, the clevis is provided with transverse slots 18 and 18a through which pass the rods 15 and 15a respectively.

The opposite sides of the box-like member 17 which are adjacent the rod-like members 15 and 15a are provided with U-shaped openings 19 and 19a which have their axes of symmetry parallel to the axis of the handle 10, and their arms pointing towards the roller 12. Passing through these U-shaped openings 19 and 19a is a yoke 20, slidably attached to the rods 15 and 15a, so that the rods may be moved forward without moving it; but projections 21 and 21a on rods 15 and 15a engage the yoke and move it with them when the rods are moved backwards. A pawl 22 is pivotally mounted within the box-like member 17 in back of the U-shaped openings 19 and 19a, and as the yoke 20 moves backward in the lower arm of the U-shaped opening, it encounters the pawl and is lifted upward, so that when the yoke is quickly moved forward, it will enter the upper arm of the U.

The rods 15 and 15a extend in a straight line from the circular sleeve 11 through the transverse slots 18 and 18a; and at a distance somewhat beyond the latter, they are offset from each other to clear roller 13 and its supporting member. At their forward ends, the rods 15 and 15a are turned towards each other and joined to form the support for the mop cloth 55.

14, offsets being provided if necessary to clear the clevises or rollers. While I have shown the mop cloth 14 held to the rods 15 and 15a by a clip 27 fitting over the cloth and pressed together so that teeth in its edges will engage the cloth and prevent it from slipping, other suitable holding means may be used.

The roller 13 is carried by a movable clevis 23 which is attached to arms 24 and 24a extending forward from a square sleeve 25 fitting around the box-like member 17. A coil spring 26, attached to the handle 10, bears against the square sleeve 25 and presses it forward, thus urging the roller 13 toward the roller 12. To provide strength and rigidity, I prefer to provide means, such as flanges on the forward ends of the clevis 23, whereby the clevis 23 will be braced by the clevis 16 and held in alignment with it. The forwardly-extending arms 24 and 24a are perpendicular to the sides of the box-like member 17 which have the U-shaped openings 19 and 19a in them, and the arms are spaced apart a sufficient distance so that they avoid the clevis 16 and extend to and support the movable clevis 23. In this way, the roller 13 is yieldably pressed against the mop cloth 14, squeezing the water out of the latter by forcing it against the roller 12.

In back of the forward-extending arms 24 and 24a, the square sleeve 25 has its top and bottom joined by sides against which the sliding yoke 20 bears, so that when the sliding yoke is moved backwards by the projections 21 and 21a, it forces the square sleeve backwards against the pressure of the spring 26, moving with it the arms 24 and 24a and separating the rollers 12 and 13. The various members are proportioned so that when the circular sleeve 11 is moved forward, the mop cloth 14 is drawn between the rollers 12 and 13; and if the circular sleeve is then returned, the free mop cloth is brought back to the rollers. At this point, assuming that the yoke 20 is in the lower arm of the U-shaped opening, the projections 21 and 21a on the rods 15 and 15a engage the yoke and force it backwards against the sides of the square sleeve 25. This movement of the sleeve separates or opens the rollers 12 and 13, and at the same time the yoke 20 encounters the pawl 22 and is raised to the upper arm of the U-shaped openings 19 and 19a, thus raising rods 15 and 15a and lifting the top of the mop cloth 14 through the space between the rollers. If the circular sleeve 11 is then released, the spring 26 will force the square sleeve 25 forward, carrying with it the roller 13 and the rods 15 and 15a.

In actual use, the mop cloth 14 may be dipped in the water or desired solution, and the cloth 60 then removed from the solution and held over the pail while the circular sleeve 11 is moved forward to wring the mop cloth, and then backwards to insert it again between the rollers 12 and 13. In this connection, it should be noted that with the 65 pawl and U-shaped transfer means illustrated, it is necessary to turn the mop over, that is, rotate it 180° with the handle 10 as an axis, after the sleeve 11 has been moved forward and before the rollers 12 and 13 have been separated preparatory to the insertion of the mop cloth 14 between them. In this way, the mop cloth is hanging down in proper position to be inserted between the rollers 12 and 13 from underneath; and in addition, the pawl 22 is rotated to the proper position to effect

the raising of the yoke 20 from the lower arm of the U-shaped openings 19 and 19a to the upper arm.

While I prefer to use this style of transfer means, since it insures the mop cloth's being inserted between the rollers with the minimum possibility of tangling, other transfer means may be used, such, for example, as that shown in Fig. 6. As illustrated there, a plate 30 is provided with two parallel slots 31 and 32 connected by a pair of cross-slots 33 and 34. The yoke 20 is guided by these slots, and springs 35 and 36 guide it into the cross-slots 33 and 34 when the yoke is moved backward, to the left in the drawings, from its forward position in slots 32 and 31, respectively. Springs 37 and 38 then permit the yoke to enter the parallel slots 32 and 31, respectively, and then close the cross-slot, so that the yoke 20 will remain in that parallel slot. Thus with this form of transfer means, no rotation of the mop is necessary to operate it; however, it is still advisable to insert the mop cloth between the rollers from below. It will be apparent, of course, that other styles of transfer means may be used to accomplish the same result by a different method.

In Figs. 7-10, I have illustrated an optional form of my invention which will find particular application where it is desired to make use of a longer mop cloth, and in other circumstances in which its advantages will become apparent.

In my optional form, I prefer to extend the rods 15 and 15a to form the mop handle, and thus I am able to eliminate the wooden handle 10, substituting in its place, the member indicated generally by the numeral 40. I prefer to make the member 40 of two pieces which, when properly assembled, provide a grip or handle 41 connected to the clevis 16 by webs 42 and 43. Outwardly-extending flanges on the upper and lower edges of the webs 42 and 43 add strength and give each web the same cross-sectional form as a structural channel; and the webs are held in parallel spaced relationship so that a sliding member 44, described hereinafter, may slide between them. The clevis 16 supports the roller 12, as in the preferred form, and transverse slots 18 and 18a are provided for the rods 15 and 15a, as previously described. The grip 41 is formed by bending enlarged portions of the flanges down and around, outside the rods 15 and 15a, to provide a comfortable handle or grip. A U-shaped opening 19 in each of the webs 42 and 43 serves the same purpose as in the preferred form, and a pair of pawls, 22 and 22a, one on the outside of each web, replaces the single pawl 22 of the previously-described form. If it is desired to have the two pawls 22 and 22a rotate together, a rivet 45 having square ends or other suitable means may be employed. A sliding yoke 20, engaged by projections 21 and 21a, moves in the U-shaped openings 19 and is transferred from one arm of the latter to the other as heretofore explained, thus raising the rods 15 and 15a.

In the space between the two webs 42 and 43 slides a member 44 which corresponds to the 65 sliding square sleeve 25 of the preferred form, and like the member 40, is preferably made of two webs 46 and 47, with flanges on their top and bottom edges, placed back to back and held together by any suitable means such as spot welding, 70 etc. Slots, such as 48, permit rivets, such as 45, to extend between the webs 42 and 43 without interfering with the sliding of the member 44; and a transverse slot 49 permits the yoke 20 to move from the lower to the upper arm of the 75

U-shaped opening 19 while at the same time providing a surface for the yoke to bear against and effect the movement of the member 44. At its forward end, the member 44 is formed into a clevis 23 which carries the roller 13, while a coil spring 26 bears against the grip 41 and the rear end of the member 44 to urge the latter and its associated roller forward.

In use, all the members cooperate in a manner similar to that of the preferred form; and the device is operated in the same way, save that instead of sliding the circular sleeve 11 forward, the grip 41 is moved backwards.

If for any reason it is desired to use the optional form, but a wooden handle is preferred, the rods 15 and 15a may be bent inwardly but not joined at their upper ends; and a handle of wood or any desired material may be attached as shown in Fig. 12. Other means of attachment may be used, of course, the one illustrated being shown by way of example only. It is possible in this way to provide various length handles which may be interchanged as the occasion demands.

In Fig. 11, I have illustrated another manner in which the handle may be made, and in this view, I have shown it made of split tubing, which possesses the advantage of being lighter while at the same time supplying the necessary strength. When this construction is used, the yoke 20, instead of fitting over the tubing, may be provided with enlargements on each end which project into the tubing while the shank of the yoke passes through the longitudinal split or slot in the tubing. If this is done, the tubing may be crimped to close the split, and the projections 21 and 21a eliminated.

While I have shown and described a preferred and an optional form of my invention, I wish it to be understood that my invention is not to be limited to the specific form or arrangement of parts herein described and shown, except in so far as limited by my claims.

I claim as my invention:

1. A self-wringing mop which includes: a handle; a first roller; a second roller; a mop cloth adapted to pass between said rollers; spring means urging said second roller toward said first roller; rod-like members supporting said mop cloth, said rod-like members being slidably mounted with respect to said rollers, whereby said mop cloth may be pulled therebetween; means for separating said rollers by the movement of said rod-like members; and means for inserting said mop cloth between said rollers while said rollers are separated.

2. A device as described in claim 1 in which the means for separating said rollers includes: a yoke slidably attached to said rod-like members; means on said rod-like members adapted to engage said yoke; and means connected to said second roller adapted to be engaged by said yoke to move said second roller away from said first roller against the urging of said spring.

3. A device as described in claim 1 in which the means for inserting said mop cloth between said rollers while said rollers are separated includes: a yoke slidably attached to said rod-like members; means on said rod-like members adapted to engage said yoke; a member having a U-shaped opening through which said yoke passes, said member being attached to said first roller; and a pivoted pawl attached to said member and adapted to transfer said yoke from one arm of said

U-shaped opening to the other arm of said opening.

4. A device as described in claim 1 in which the means for separating said rollers includes: a yoke slidably attached to said rod-like members, means on said rod-like member adapted to engage said yoke, and means connected to said second roller adapted to be engaged by said yoke to move said second roller away from said first roller against the urging of said spring; and the means for inserting said mop cloth between said rollers while said rollers are separated includes a member having a U-shaped opening through which said yoke passes, said member being attached to said first roller, and a pivoted pawl attached to said member and adapted to transfer said yoke from one arm of said U-shaped opening to the other arm of said opening.

5. A self-wringing mop which includes: a handle; a box-like member on the lower end of said handle, said member having U-shaped openings in a pair of opposite sides; a first roller attached to said box-like member by a clevis having a transverse slot therein; a sleeve member slideable on said box-like member; a second roller attached to said sleeve member and which may bear against said first roller; a spring urging said sleeve member toward said first roller; a sliding sleeve on said handle having attached thereto a rod-like member passing through said transverse slots in said clevis and carrying a mop cloth on its lower end; a yoke passing through said U-shaped opening and slidably attached to said rod-like member; engaging means on said rod-like member for engaging said yoke and causing it to move said first-mentioned sleeve away from said first roller, separating said first and said second rollers; and a pawl pivotally attached to said box-like member adjacent the base of said U-shaped slots to transfer said yoke from one arm of said U-shaped slot to the other arm of said slot.

6. A self-wringing mop which includes: a handle; a mop cloth attached to said handle; a first member slidably attached to said handle and carrying a first roller, said member being provided with a U-shaped slot; a pawl pivotally attached to said member adjacent the base of said U-shaped slot; a yoke slidably attached to said handle and guided by said U-shaped slot; a second member slidably attached to said first member; a second roller attached to said second member and located so as to be capable of squeezing said mop cloth against said first roller; a spring bearing against said first member and said second member, urging said second member toward said first roller; and engaging means on said handle to engage said yoke and cause said yoke to move said second member away from said first roller.

7. A self-wringing mop which includes: a first roller; a second roller yieldably urged toward said first roller; a mop cloth; rod means carrying said mop cloth on one end thereof, said rod means being slidable with respect to said rollers in a plane substantially parallel to the plane determined by the axes of said rollers, whereby said mop cloth may be pulled therebetween; and means for inserting said mop cloth between said rollers.

8. A self-wringing mop which includes: a first roller; a second roller yieldably urged toward said first roller; a mop cloth; rod means carrying said mop cloth on one end thereof, said rod means being slidably mounted with respect to said rollers

whereby said mop cloth may be pulled therebetween; and means for inserting said mop cloth between said rollers, said means including means for separating said rollers.

5 9. A self-wringing mop which includes: a first roller; a second roller yieldably urged toward said first roller; a mop cloth; rod means carrying said mop cloth on one end thereof, said rod

means being slidable with respect to said rollers in a plane substantially parallel to the plane determined by the axes of said rollers, whereby said mop cloth may be pulled therebetween, and means for inserting said mop cloth between said rollers, said means including means for separating said rollers.

5 VIRGIL K. COOPER.
